UNITED STATES PATENT OFFICE

150,739

DESIGN FOR A VANITY

Clytie Ann Thomson, Roanoke, Va.

Application February 10, 1947, Serial No. 136,810

Term of patent 3½ years

(Cl. D33--6)

To all whom it may concern:

Be it known that I, Clytie Ann Thomson, a citizen of the United States, residing at Roanoke, Virginia, in the county of Roanoke and State of Virginia, have invented a new, original, and ornamental Design for Vanity, of which the following is a specification, reference being had to the accompanying drawing, forming part thereof.

The figure is a front perspective view of a vanity, showing my new design.

The sides of the vanity pedestals, not shown, and the back thereof are essentially plain.

I claim:

The ornamental design for a vanity, as shown and described.

CLYTIE ANN THOMSON.
